UNITED STATES PATENT OFFICE.

THOMAS JOHN GEE, OF CHATTERIS, ENGLAND.

SWINGING FEED-ELEVATOR FOR MAIZE-SHELLERS AND THRESHING-MACHINES.

No. 880,291.

Specification of Letters Patent.

Patented Feb. 25, 1908.

Application filed October 4, 1907. Serial No. 395,824.

To all whom it may concern:

Be it known that I, THOMAS JOHN GEE, a subject of the King of the United Kingdom of Great Britain and Ireland, and residing at 5 Chatteris, Cambridgeshire, England, have invented a certain new and useful Improvement in Swinging Feed-Elevators for Maize-Shellers and Threshing-Machines, of which the following is a specification.

10 This invention relates to an improved construction of swinging elevator, suspended from an upper circular framework, and designed for conveying corn, maize or any other class of cereals from the ground level or from 15 the stack, and delivering the same to the threshing cylinder of the machine.

The elevator revolves on a central pivot and has a circular motion by which means it can feed the threshing machine from either 20 side and also from the end of the same, the elevator being also arranged to feed the machine at varying heights either from the ground level or from the top of a stack, thereby securing a great economy in time 25 and labor. To this end I employ a fixed wheel-shaped framework, upon whose outer rim the elevator revolves by means of guide rollers.

In the accompanying drawings which illustrate the invention, Figure 1 is a side elevation of the swinging portion of the elevator suspended from the fixed circular framework. Fig. 2 is a sectional view of the same on the line X--Y of Fig. 1.

35 Referring to the drawings *m m*, denote the iron supports from which the elevator is suspended.

n is the fixed framework built in the form of a wheel, whose hub of cast iron or 40 the like forms the central pivot and whose rim connected to the hub by spokes or arms constitutes the outer rail from which the elevator is suspended.

o is a collar having internal screw threads 45 fitted to the lower portion of the central hub or pivot of the framework *n* and secured by a set screw *o*¹.

p is a revolving bracket having projecting lugs for receiving the suspension brackets *r*, 50 *r*, which carry the elevator box.

q is a bearing bracket secured to the bracket *p*.

s is the upper roller of the elevator carrier.

t is an iron plate secured to the suspension brackets *r*, *r*, to which plate are fitted guide 55 rollers *u*, *u*, which run on the outer rim of the frame-work *n*.

v is the upper horizontal spindle for transmitting the motion through a short vertical spindle *w* to the spindle *q*¹ of the bracket *q*. 60

The working of the apparatus is as follows:—The bracket *p* revolves on the hub or pivot of the framework *n*. The plate *t* revolves with the brackets *r*, *r* and the small guide rollers *u*, *u*, which serve to support the elevator box roll around the outer rim of the framework *n*. Thus by moving the bracket *p* the entire elevator can be swung to any desired position. By means of the upper horizontal shaft *v* the motion obtained from the 70 threshing machine is transmitted to the short spindle *w*, from this spindle to the spindle *q*¹ in the bearing *q* and thence by means of the chain gearing *A* to the roller *s* of the elevator carrier which feeds the grain or maize to the 75 threshing cylinder. The elevator can be raised and lowered by means of a rope attached to a winding drum and the elevator carrier is free to travel in vertical or horizontal direction as will be understood. 80

Having now described my invention what I claim and desire to secure by Letters Patent of the United States is:—

The improved apparatus for feeding maize shellers and threshing machines comprising 85 channel iron supports *m*, a stationary horizontal wheel-shaped frame-work *n* fixed to said supports, a bracket *p* revolving around the hub of the framework arms *T* connected to said bracket, a swinging elevator, carried 90 by said arms, rollers *u* secured to said arms and rolling on the rim of said frame work, and gearing for operating said elevator, substantially as described.

In testimony whereof I have signed my 95 name to this specification in the presence of two subscribing witnesses.

THOMAS JOHN GEE.
